(57) **CLAIM**

The ornamental design for a main body of dehumidifying, deodorizing and wrinkle-reducing machine for clothing as shown and described.

DESCRIPTION

1. Main body of dehumidifying, deodorizing and wrinkle-reducing machine for clothing

1.1 : Perspective

1.2 : Front

1.3 : Back

1.4 : Left

1.5 : Top

1.6 : Bottom

1.7 : Reference view

1.8 : Perspective view 2

1.9 : Front view 2

1.10 : Back view 2

1.11 : Left view 2

1.12 : Right view 2

1.13 : Top view 2

1.14 : Bottom view 2

1.15 : Reference view 2

1.16 : Perspective view 3

1.17 : Front view 3

1.18 : Back view 3

1.19 : Left view 3

1.20 : Right view 3

1.21 : Top view 3

1.22 : Bottom view 3

The broken lines depict portions of a main body of dehumidifying, deodorizing and wrinkle-reducing machine for clothing that form no part of the claimed design; reproductions 1.1 to 1.6 are front perspective, front, back, left, top and bottom views of the main body of dehumidifying, deodorizing and wrinkle-reducing machine for clothing, and the right view is a mirror image of the left view; reproduction 1.7 is a reference view showing a process in which the pants press has been slid out from the inside thereof, and

(Continued)

forms no part of the claimed design; reproduction **1.8** is front perspective view in a condition that the pants press has been slid out completely; reproductions **1.9** to **1.14** are front, back, left, right, top and bottom views of the reproduction **1.8**; reproduction **1.15** is a reference view showing a process in which the pants press has been slid out and its door opened, and forms no part of the claimed design; reproduction **1.16** is a front perspective view in a condition that the pants press has been slid out and its door opened completely; reproductions **1.17** to **1.22** are front, back, left, right, top and bottom views of reproduction **1.16**; this is a design for a main body of dehumidifying, deodorizing and wrinkle-reducing machine for clothing with a pants press inside thereof; as shown in reproduction **1.7**, the pants press is slid out from the inside of the main body, and then, as shown in reproduction **1.15**, the door is opened and used to hang pants, etc.
